UNITED STATES PATENT OFFICE.

JULIUS STONE CHRISTMAS, OF CHARLESTON, WEST VIRGINIA.

RAIL FASTENER.

Application filed March 12, 1924. Serial No. 698,794.

To all whom it may concern:

Be it known that I, JULIUS STONE CHRISTMAS, a citizen of the United States, and a resident of Charleston, in the county of Kanawha and State of West Virginia, have invented certain new and useful Improvements in Rail Fasteners, of which the following is a specification.

This invention is an improvement in rail fasteners, and is especially designed for use with mine railways of the type employing steel rails.

The object of the invention is to provide a rail fastener of this character which may be readily assembled with the tie and rail or released and which when assembled with the rail and tie firmly and securely locks and holds the rail to the tie.

A further object is to provide a rail fastener of this character and having these advantages and which is also of simple and durable construction, reliable in operation and easy and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a fragmentary perspective view, showing one embodiment of the invention;

Figure 2 is a fragmentary plan view of the same with the tread of the rail broken away for the sake of illustration;

Figure 3 is a view in central longitudinal vertical section; and

Figure 4 is a fragmentary group view in perspective illustrating the interengaging means between the locking bar and the tie.

In the drawings a steel tie 5 of channel form has integral fixed rail engaging jaws 6 at its ends. One side of the base of each rail 7 is engaged by a jaw 6 and the opposite side is engaged by the rail fastening device constituting the present invention and designated generally at 8. As these rail fasteners 8 are of identical construction a single description will serve for both.

Each rail fastener 8 includes a spring locking bar 9 which is preferably constructed of spring steel so as to have the requisite resiliency and strength. Intermediate its

ends the bar 9 is slidably and pivotally connected to the tie. For this purpose the bar 9 is provided with a longitudinal slot 10. A rivet 11 is fixedly secured to the tie 5 and has a rounded portion 12 of its shank extended through the slot 10 of the bar 9, the rounded portion 12 having a sliding and rotary fit in the slot 10. The length of the rounded portion 12 of the shank of the rivet 65 is somewhat greater than the thickness of the bar 9, for a purpose which will presently appear. A head 13 of the rivet 11 is engageable with the top side of the bar 9 along the slot 10.

One end of the bar 9 is upwardly inclined, as at 14, and is engageable with the base of the rail. At its opposite end the bar 9 has integrally formed therewith a depending tongue 15, the lower edge of which is curved as indicated at 16 and as shown to advantage in Figure 4. A transverse groove 17 is provided in the tie 5 and has a curved bottom wall 18 with which the tongue 15 is cooperable as will presently appear.

In operation, the rail is first engaged with the fixed jaw 6, the bar 9 having been shifted to the extreme right as viewed in Figures 1 to 3, and as shown in dotted lines in Figures 2 and 3. To assemble the rail fastener with the rail it is moved to the left as viewed in Figures 1 to 3 until the upturned end 14 comes into engagement with the top surface of the base of the rail 7 adjacent the side edge thereof. This initial movement is freely partaken of by the bar 9 due to the greater length of the portion 12 of the shank of the rivet 11. The top surface of the base of the rail inclines upwardly from its side edges to the web of the rail so that after the initial movement described the portion 14 comes into tight frictional engagement with the base of the rail. The bar 9 is, however, driven along the tie 5 to the left, as viewed in Figures 2 and 3 to cause the end portion 14 of the bar to ride up the base of the rail until the tongue 15 snaps into the groove 17.

The bar 9 is thus flexed longitudinally about the head 13 of the rivet 11, the end 14 of the bar being elevated above the rivet by virtue of its engagement with the base of the rail and the other end of the bar being elevated above the rivet by the tongue 15. Since the bar 9 is constructed of spring steel it firmly locks and secures the rail to the tie. Endwise displacement of the bar 9 is prevented by the engagement of the end 14 with the

rail and by the engagement of the tongue 15 with the slot 17. Due to the curvature of the lower edge 16 of the tongue 15 and to the corresponding curvature of the bottom wall 18 of the groove 17, the bar 9 may be released from its engagement with the rail by driving the same in either direction about the rivet 11 as an axis, as indicated in dotted lines in Figure 2, although, of course, the frictional engagement of these parts securely holds them against accidental displacement. A hammer may be used to drive the locking bar in both the assembling and releasing operations, the hammer being struck against the bar at the juncture of the tongue 15 therewith.

I claim:

1. A rail fastener for use in securing a rail to a tie and including a spring locking bar slidably and rotatably connected to the tie, said bar being flexed longitudinally in the assembly and having one end engaged with the rail, and interengaging means between the opposite end of the locking bar and the tie.

2. A rail fastener for use in securing a rail to a tie and including a spring locking bar slidably and rotatably connected to the tie, said bar being flexed longitudinally in the assembly and having one end engaged with the rail.

3. A rail fastener for use in securing a rail to a tie and including a spring locking bar having its intermediate portion slidably and pivotally connected to the tie and having one end upwardly inclined and engageable with the rail, and interengaging means between the opposite end of the bar and the tie, the bar being flexed longitudinally in assembly.

4. A rail fastener for use in securing a rail to a tie and including a spring locking bar having its intermediate portion slidably and

pivotally connected to the tie and having one end upwardly inclined and engageable with the rail, and interengaging means between the opposite end of the bar and the tie, said interengaging means including a tongue depending from the locking bar, the tie having a transverse groove provided with a curved bottom wall with which the tongue is cooperable, the bar being flexed longitudinally in assembly.

5. A rail fastener for use in securing a rail to a steel tie having a fixed rail engaging jaw, said rail fastener including a locking bar of spring steel, said locking bar being curved longitudinally and having one end upwardly inclined and engageable with the base of the rail and having a depending tongue at its opposite end provided with a curved lower edge, said bar having a longitudinal slot intermediate its ends, a rivet secured to the tie and upstanding therefrom, said rivet having a shank slidably and rotatably fitted in the slot of the bar and having a head engaged with the upper side of the locking bar, the tie having a transverse slot into which the depending tongue of the bar snaps in assembly.

6. A rail fastener for use in securing a rail to a tie having a fixed rail engaging jaw, said rail fastener including a locking bar of spring steel having its intermediate portion slidably and pivotally connected to the tie and having one end engageable with the rail, said bar having a depending tongue at its opposite end, the tie having a groove cooperable with the tongue, the locking bar being longitudinally flexed in assembly and being spaced from the tie whereby the inherent resiliency of the bar holds the same in position and clamps the rail to the tie.

JULIUS STONE CHRISTMAS.
